[57] **CLAIM**

The ornamental design for a box for containing and
protecting a cap, as shown and described.

DESCRIPTION

FIG. 1 is a perspective view of a box for containing and
protecting a cap showing my new design;

FIG. 2 is a rear elevational view thereof;

FIG. 3 is a top plan view thereof;

FIG. 4 is a right side elevational view thereof; the oppo-
site side being a mirror image;

FIG. 5 is a front elevational view thereof;

FIG. 6 is a bottom plan view thereof.

FIG. 1

FIG. 2

FIG. 3

FIG. 4

FIG. 5

FIG. 6
